UNITED STATES PATENT OFFICE.

FRED T. BURNHAM, OF NEWTON CENTER, MASSACHUSETTS.

TUMBLER-WASHING MACHINE.

Application filed December 29, 1925. Serial No. 78,086.

The invention has relation to washing machines of the class designed for washing tumblers, cups, other dishes, cans, bottles, other containers, and the like.

- 5 The objects of the present invention are to provide a novel and improved machine, compact, capable of being tended by one operator instead of two, as heretofore in some instances, simple in construction, easy and
 10 thorough as well as inexpensive in operation, free from likelihood of breaking tumblers or other articles operated upon, and adapted in size and appearance to be located and employed in full public view and at the point
 15 where the washed tumblers or other articles operated upon are to be delivered and removed from the machine.

The invention consists in various novel combinations and constructional features, 20 and a novel organization, all designed for the attainment of the foregoing and other special objects.

A machine comprising an illustrative embodiment of the invention is shown in the 25 accompanying drawings, in which,—

Fig. 1 is a front elevation of such machine.

Fig. 2 is a front view thereof, with the upper half of the machine in vertical section on line 2—2 of Fig. 3.

30 Fig. 3, Sheet 2, is a view in horizontal section on line 3—3 of Fig. 1, with the tray to receive the washed articles detached.

Fig. 4 is a bottom view of the machine.

Fig. 5, Sheet 3, is a view showing the machine in vertical section on the irregular line 5—5 of Fig. 3.

Fig. 6 is a plan view of the base section containing two tanks and certain associated parts.

40 Fig. 7 is a view in vertical section of the circulating pump, this view being on a larger scale than the views already mentioned.

Fig. 8 is a detail plan view, also on enlarged scale, of the friction clutch by which 45 the conveyor is driven.

Fig. 9 is a view in vertical section on the enlarged scale of the pipe and outlets supplying the rinsing streams of water to the inside of the tumblers or other articles operated upon.

50 Fig. 10 is a plan view of the tray to which the articles are delivered as they complete their passage through the machine.

Having reference to the drawings,—

55 The machine shown in the drawings is circular in plan, so that the tumblers or other

articles to be cleansed, after being presented to the machine, may perform the necessary travel through the machine while being subjected to the various processes, and then be 60 delivered close to their starting point, so as to enable one operator to feed the articles into the machine as well as attend to their removal following their discharge from the carrier by which such travel is produced. 65

The supporting framework is made in sections, viz: a housing 1 which encloses the space which is occupied by the glasses while under treatment, and also by the overhead washing and rinsing devices, an intermediate 70 section 2 within which are located the conveyor and the lower washing and rinsing devices, a main base section 3 within which are located the motor and driving connections, 75 circulating pumps, drains, etc., and a tank-section 4 located at the front of said main base-section 3.

The housing 1 is made removable from the intermediate section 2, being in this instance capable of being lifted off by means of handles 49, 49, provided on the top 6 thereof. This removal will afford access to the working parts it encloses, and to the carrier or conveyor, for cleaning, etc. The lower edge of the shell of housing 1 rests on a seat within a flange 7 on the top edge of the intermediate section 2, brackets 15, 15, Figs. 1 and 2, being applied to the exterior of the said shell to hook over the top of said flange. Housing 1 is provided with windows 8, 8, Figs. 1 and 2, 80 about its wall, formed of bent glass set in rubber packing strips 9, 9, of H-shaped section which embrace the edges of both the glass and the metal of the housing to form a water-tight seal. Through these windows 85 the interior of the said housing may be inspected. The space at the center of housing 1 is shown as utilized as a storage space for the supply 10, Figs. 2 and 5, of washing powder, 90 soap, or other material used in the tank containing the washing liquid, an oblong receptacle 100 being made part of the removable housing unit 1 for this purpose, such receptacle being equipped with a removable cover 11 which fits about a raised flange or bead 12, 95 Figs. 2 and 5, rising from the top 6 of the housing. A foot 13 is shown on the bottom of the receptacle 10, resting in a depression in the top of the elevated central portion 14 of the section 2. The front of the vertical 100 wall of said housing 1 is cut away as indicated in Fig. 1, the space from edge 16 to

edge 17 of the opening thus formed affording access to the interior to permit the tumblers or other articles operated upon to be placed inside said housing upon the conveyor for 5 washing, and to allow exit of the tumblers, etc., after making the circuit of the machine.

The intermediate section 2 of the machine is in the form of a basin with a raised central portion 14 upon the crown of which is fixed a 10 circular track 19, L-shaped in cross-section, secured by screws 20, 20, 20, Fig. 3, to the said crown. On this track rests the inner marginal portion of the conveyor, which is annular. The said inner marginal portion is in the 15 form of an internally toothed gear 21, Fig. 3, and from the same radiate a plurality of members 22, 22, Fig. 3, supporting a number of concentric circular tumbler-supporting members 23. This conveyor has combined 20 operatively with it driving mechanism by which it is rotated slowly. In the present instance the said driving mechanism includes a vertical shaft 25, Fig. 5, and a gear 24 at the upper end of such shaft intermeshing with 25 the internally toothed gear 21. A suitable slip-connection is embodied in the said driving mechanism, in order that the conveyor may be driven in a yielding manner, so that in case of jamming of the tumblers within the 30 housing 1 the conveyor may stop moving rather than cause the tumblers to be broken. In the present instance, also, the slip-connection is located between the shaft 25 and the gear 24, the latter being so related to the shaft 35 as to enable one thereof to turn independently of the other. The slip-connection comprises a friction clutch shown separately in Fig. 8 consisting of a flange 26 in connection with the gear 24, and two friction-shoes 27, 27, within the said flange, positively driven from shaft 25 by means of an H-shaped member 28 keyed to said shaft and having opposite recesses into which tongues 29, 29, on said shoes 27, 27, enter. Expanding coil springs 30, 30, between 40 the opposed extremities of the clutch-shoes 27, 27 hold the latter normally in sufficiently firm engagement with the interior of the flange 26 to insure rotation of the gear 24 and hence of the conveyor so long as no undue 45 resistance to rotation arises through jamming. The shaft 25 receives its rotation through a worm-gear 31 fixed upon its lower end, and a worm 32, Figs. 4 and 5, upon a jack-shaft 33, the latter driven by means of a worm-gear 330 and worm 331 from the shaft 34 of an 50 electric motor 35 mounted within the base 3 of the machine and controlled by a switch 96 on the outside of the base. The shafts 25 and 33 and their worm gearing are encased in 55 housings 37 and 36, the housing 37 extending vertically upward through the bottom of the intermediate section 2 and being secured thereto by bolts 371 passing through a flange 38 formed on said housing. Ball-bearings 251, 251, are provided for the upper and lower 60

70 portions of shaft 25 in connection with this vertical housing, and a skirt or flange 39 in connection with the gear 24 encircles the upper end of the housing with its enclosed ball-bearing and extends some distance down within the basin-shaped intermediate section 2, for the purpose of preventing access of water 75 to the upper ball-bearing. To prevent water which may work upward between the housing 37 and the skirt or flange 39 from reaching the upper bearing from below, a plurality of circumferential water-detaining grooves is made around the upper end of said housing, as indicated in Fig. 5.

In the present machine, as heretofore in 80 many instances, the cleansing of the tumblers or other articles operated upon is performed by the use of jets of water. In the present machine the mechanism is preferably designed to perform first the washing of the tumblers 85 with soap solution, second, a preliminary rinsing of the tumblers with disposal of the rinse water into the drain or waste pipe and thence out of the machine, and third, a final rinsing of the tumblers with water which is 90 used over again. To these ends, the machine is equipped with a tank 40 in the removable tank section 4 to hold a washing liquid, which in practice may be composed of water having dissolved in it soap powder or washing powder of some sort, and with a tank 41 in said base portion to hold rinsing fluid, which may be clear or substantially clear hot water. Both of these tanks are coupled with a source 95 of water supply, which may be the water supply system of the building in which the machine is installed, preferably a system including water heating provisions. The tanks 40, 41, are provided with inlet-valves 42, 42, controlled in well-known manner by floats 100 43, 43, which admit additional water into the respective tanks when the contents of the latter falls below a predetermined point. In addition, the tank 40 is provided with electric heaters 44, 44, controlled by a switch 451 on the exterior of the machine, to insure the washing solution being kept at a sufficiently high temperature. Communication is established by means of a pipe 45, Fig. 4, between 105 the interior of the soap solution tank 40 and one chamber of a rotary circulating double pump 46, Figs. 4 and 7, the rotors 461, 462, of which are driven by the shaft 34 of the electric motor 35, aforesaid. This rotary pump, shown in section in Fig. 7, is adapted 110 to circulate both the soapy and the clear water from the two separate tanks 40, 41; the soapy water entering from pipe 45 into the space 47 of the pump-casing and being forced out by the rotor 461 through outlet 48 and a pipe 49, Fig. 4, into a manifold 50, Fig. 2, within a chamber 511 of intermediate framework section 2, the said manifold having laterally-extending branches 51, Figs. 2 and 3, underlying the conveyor and concentric therewith. 115 120 125 130

The said manifold has an upright branch, 501, Fig. 2, which passes upward inside the track 19, within a recess formed in the crown of the raised central portion 14 of section 2, and thence extends radially outward, within a washing chamber 502, Fig. 2, such branch terminating in short transversely extending sections 52, Figs. 2 and 3, located at a sufficient height above the conveyor to permit free passage of tumblers and the like beneath them as the conveyor rotates. The branches 51 and 52 are provided with a plurality of holes as at 511, Fig. 3, through which jets of soapy water will be projected when the pump 46 is in operation. The holes thus permitting the issuance of the soapy wash water are made of large diameter, to reduce the likelihood of their being clogged by bits of food and other débris passing into the wash water in the course of the use of the machine. In connection with the jet holes in the upper branch 52 there are provided spreaders 53, 53, Figs. 2 and 3, against which the issuing jets of water impinge, to be deflected downward in a fan-shaped spray which will be sure to cover all external portions of the tumblers or other articles disposed on the conveyor below them, as the latter are carried past in the movement of the conveyor. The holes in the branch 51, beneath the conveyor, are likewise provided with deflectors on the order of those shown in large scale at 54 in Fig. 9 in connection with another part of this machine, which serve to spread the jets upwardly fan-wise, but to a lesser degree than the devices 53 just described, for the purpose of insuring all portions of the interiors of the articles placed upon the conveyor in inverted position being reached by the soap solution. After issuing from the jets as aforesaid, and having acted upon the articles, the soapy water descends within the annular chamber of the basin-shaped section 2, between a radial partition wall 56, Fig. 3, at the front of said section and a similar wall 55 at the rear end of branch 51, and drains back into the tank 40 through screens or strainers provided in covers 57, 57, Figs. 3 and 5, which are fitted to a plurality of clean-out holes formed in the bottom of section 2 directly over tank 40. Thus the soapy water is economically used over and over again until its condition becomes such as to necessitate its being discarded, it being necessary simply to lift a plug exactly similar to that illustrated in Fig. 5 at 58, in connection with the rinse water tank, by means of a finger-hold 59, to permit the contents of the tank 40 to flow out through the drainage hole 60 and outlet 61. It is to be noted that the suction pipe 45 extending from the tank 40 to the pump 46 has its intake located at such height that at no time shall the water level in tank 40 be reduced low enough to uncover the electric heating arrangements. Thereby overheating of the latter, and resulting in-jury are avoided. To guard against the water rising too high in either the wash-water tank 40 or the adjoining rinse-water tank 41, as for instance in case the float valves should fail to shut off the inflow from the source of supply at the right level, outflow of the excess from the respective tanks is provided for by forming in an expanded portion of the partition wall between the two tanks a well 63 communicating at its bottom with outlet 61. The upper edges of the portions of the said wall surrounding the said well are slightly lower than the main portion of the wall, being at a height corresponding with the limit to be reached by the water. The wall keeps the contents of the two tanks from mixing. When the water in either tank rises above the edges of the well, it overflows into the well 63 and out through the outlet 61.

The tank 41, Fig. 6, which is intended to contain clear hot water for rinsing the articles after they have been washed by the soapy solution, is very similar in construction to the soapy water tank 40 just described. It is connected to the water supply of the building at 64, just as is the soapy water tank, fresh water being admitted under control of float valve 42. It may be equipped with water-heating devices as in the case of the wash-water tank 40, but if the connection at 64 is with a supply system furnishing hot water, the latter will answer for rinsing purposes. Water is drawn from this tank 41 through an intake 65, Figs. 4 and 6, and through pipe 66 to the other side of the double pump 46, being admitted at 67, Fig. 7, and expelled by the rotor 462, at 68, passing thence through a pipe 69 and an opening 70 (see particularly Fig. 9) in the bottom of the section 2 into a manifold 72 that is partly contained within a short compartment 721, Figs. 3 and 5, divided off by partitions 55 and 71, Fig. 3, which extend up from the bottom of the annular trough-like portion of section 2. The said manifold 72 extends a short distance around the machine beneath the conveyor, rising in a bend over the partition 71, Fig. 9, and having a branch 73 which extends upward inside the track 19 and radially outward and terminates in branches 74 extending transversely above the conveyor within a rinsing chamber 722, Fig. 2. Both the portion of said manifold underlying the conveyor, and the branch 74 extending out over the conveyor at a considerable height thereabove, are provided with holes, as 724, Fig. 3, from which jets of water issue when the motor 35 rotates the pump 46. As in the case of the manifold for the soapy water, these holes have adjacent deflectors 75, 75, Fig. 3, in the case of the overhead branch 74, and smaller deflectors 54, 77, Fig. 9, in connection with the underlying portion of the manifold, for spreading the streams issuing from the holes fan-wise. It is to be

noted that one hole 76 is provided in the manifold within the compartment of section 2 that is defined by partitions 55 and 71. The deflector 77 in connection with this 5 hole 76 has a considerable curve to its portion which is in the path of the stream which issues from this hole. The effect of this is to cause the water issuing from the hole 76 to be deflected so that it will pass over the 10 partition 71 and descend into the compartment lying between partition 71 and partition 56 at the front of the machine, so long as no tumbler or other vessel is in position above said hole to block said spray from so 15 doing. The rinse water thus falling within the latter compartment, together with the rinse water simultaneously issuing from the balance of the holes in said manifold 72, then drains back into the rinse-water tank 41, for 20 use over again, through openings formed above tank 41 in the bottom of section 2 and fitted with covers 57 equipped with strainers, said covers being removable for cleaning purposes. When a tumbler or other article resting 25 upon the conveyor in inverted position is carried over the hole or outlet 76 after being subjected to spraying with the soap solution, all the water entering into the tumbler, etc., from this outlet drips back into 30 the compartment bounded by the partitions 55 and 71, and is allowed to run out through a hole 78, Figs. 3 and 5, in the bottom of the compartment, through a pipe 79, Figs. 4 and 5, into a passage 80, Figs. 5 and 6, between 35 the two tanks 40 and 41, and thence into the outlet 61 and out of the machine. In this way, the rinse-water within the tank 41 is kept clean throughout repeated uses, as the articles are given a preliminary rinsing as 40 they travel over outlet 76 and deflector 77, to remove the bulk of the soapy wash-water, and the water thus used is not allowed to return to the rinse-water tank. Yet economy is sub- 45 served inasmuch as when no article is in position over the outlet 76, the water discharged here passes over the partition 71 into the compartment receiving the water used in the final rinsing and thence to the rinse-water tank 41, and there is no wastage. In other 50 words, the wastage of water, other than necessitated by changing the soap solution, is only that of the preliminary rinsing, and is proportional to the number of articles washed, and no water ordinarily leaves the machine 55 except such as is actually applied to the articles in the preliminary rinsing. If desired, of course, this preliminary rinsing may be dispensed with, by omitting outlet 76, or plugging it up, or otherwise. Under ordinary 60 conditions of use, it is not contemplated to install a heater in the rinse-water tank 41, as under the control of float-valve 42 in connection with the said tank the lowering of the level in such tank as a result of the wast- 65 age of water in the preliminary rinsing will

cause a flow of fresh hot water from the hot water supply of the building into such tank. To insure the soapy wash water and the rinse-water falling within their proper tank-compartments, a curtain 81, Fig. 5, made up 70 of a number of narrow strips of rubber suspended from inside the top 6 of the housing 1 is placed over the partition 55, such curtain easily parting to let through a tumbler or other article resting on the moving conveyor 75 but stopping the spattering water. Similar curtains 81 are employed at the points where the tumblers or other articles enter and leave the housing 1, to prevent spattering of the water out of the machine. The articles operated upon are placed upon the conveyor by hand at the front of the machine where the housing is open, adjacent edge 16, but are automatically delivered onto an inclined tray 82, Figs. 5 and 10, removably held onto the 80 front of the machine by forked brackets 83, Fig. 5, which fit over the rim of section 2 at the front of the latter, a finger 84 being secured at 85 to one corner of the tray to extend across the conveyor obliquely and divert the articles from it onto the tray as they are brought into contact with said finger through the rotation of the conveyor. A drainage hole 86 is made in the tray to let off the water draining from the wet articles, a 90 detachable flexible tube 87 leading such water into the drain or outlet 61.

In the drawings, the bearings of shaft 34 of the circulating pump have no packing. The said shaft 34 is supported by a short 100 bearing between the two rotors, and by a long bearing 88 between the rotors and the motor 35. Alongside bearing 88 the shaft support is formed with a chamber 89 within which is a flange 90, fixed on the shaft, 105 and serving to throw off within the chamber 89 the water which works along the shaft through such bearing 88. A tube 91, Fig. 4, connected with a nipple 92, Fig. 7, in a hole in the bottom of this chamber conducts this 110 leakage into the pipe 79, Fig. 4, whence it escapes into the drain. Further, in order to facilitate the cleaning of the soap solution and rinse tanks without removal of the housing 1 and the conveyor, which by the way are 115 simply lifted off without any particular manipulation being necessary, the section 2 is provided with additional clean-out holes having covers 93, 93, Fig. 3, equipped with strainers, made in a part of section 2 extending 120 out like a shelf in front of the machine, and giving access to generous passages occupying the bulges at 94, 95, Figs. 1 and 2, on the base 3 and communicating with the tanks 40 and 41, so that it is an easy matter to reach 125 in and swab out the interior of such tanks by hand at any time. In general, the whole machine is designed to be kept in sanitary condition and in efficient running order with a minimum of effort.

The machine illustrated and described herein is very compact and occupies very little floor space. It can be attended by one operator, instead of two or more. As will be apparent, thoroughness of cleansing is provided for.

What is claimed as the invention is:—

1. A machine for cleansing tumblers and other like articles, comprising a moving conveyor for the articles to be cleansed, jet devices for discharging washing fluid upon the articles moved along by the conveyor, a jet device for effecting preliminary rinsing of the washed articles as they are advanced by the conveyor, jet devices for final rinsing of said articles, separate receivers for the fluid which has been used in washing and that which has been used in the final rinsing, a waste-outlet for fluid used in preliminary rinsing, and means for producing flow of the washing fluid from its receiver to the corresponding jet devices and producing flow of the rinsing fluid from its receiver to the other jet devices to be used for both preliminary and the final rinsings.
2. A machine for cleansing tumblers and the like articles, comprising a moving conveyor for the articles to be cleansed, jet devices for discharging washing fluid upon the articles moved along by the conveyor, jet devices for fluid used for final rinsing of the said articles, separate receivers for the fluid which has been used in washing and for that

which has been used in the final rinsing, a jet device for preliminary rinsing which in the absence of an article to be rinsed discharges into the rinsing fluid receiver, a waste-outlet through which the fluid that has been used in the preliminary rinsing makes its exit, and means for producing flow of washing fluid from its receiver to the corresponding jet devices and of rinsing fluid from its receiver to the other jet devices to be used for both preliminary and the final rinsings.

3. A machine for cleansing tumblers and other like articles, comprising a moving conveyor for the articles to be cleansed, jet devices for discharging washing fluid upwardly and downwardly upon the moving articles, a jet device at a preliminary rinsing station for discharging rinse-fluid upward into the interior of inverted tumblers and the like to effect a preliminary rinsing of the said interior, a waste-outlet for the fluid used in such preliminary rinsing, jet devices at a final rinsing station for discharging rinse-fluid upwardly and downwardly upon the moving articles to effect a final rinsing thereof, separate receivers for the wash-fluid and final rinse-fluid, and means for returning fluid from one receiver to the washing jets and from the other to the rinsing jets at both rinsing stations.

FRED T. BURNHAM.
